UNITED STATES PATENT OFFICE.

JOHN TOM BESWICK, OF NEW YORK, N. Y.

ELECTRIC FAN.

SPECIFICATION forming part of Letters Patent No. 660,551, dated October 30, 1900.

Application filed May 8, 1900. Serial No. 15,987. (No model.)

To all whom it may concern:

Be it known that I, JOHN TOM BESWICK, a citizen of the United States, residing at New York city, borough of Brooklyn, county of 5 Kings, State of New York, have invented certain new and useful Improvements in Electric Fans, of which the following is a specification.

My invention relates, first, to the containing-case and its supporting-standard, by reason of which a great variety of positions may be given to the fan; second, to the construction of the containing-case, whereby the cost of the motor may be materially reduced and the various parts quickly removed for inspection and repair; third, to the combination, with the containing-case, of detachable side plates carrying adjustable contact-brushes, whereby the interior of the case may be easily inspected and the brushes adjusted or removed, and, fourth, to the construction of the guard for the rotating fan, by means of which the fan is protected and the guard not easily bent or broken when subjected to blows.

The accompanying drawings will serve to 25 illustrate my invention.

Figure 1 is a view in perspective with one of the side plates of the containing-case removed. Fig. 2 is a view in perspective of the containing-case with one bearing removed. 30 Fig. 3 is a vertical section. Fig. 4 is an elevation and partial vertical section taken at right angles to that of Fig. 3. Fig. 5 is a partial transverse section taken through the guard.

Similar letters of reference indicate like parts throughout the several views.

In the drawings, A represents the standard or base, the upper end of the interior of which (best shown at Fig. 3) is made concave at B 40 and has a slot cut through it at C.

D is the containing-case. Interposed between the containing-case D and the concave portion of the base A is a column E, which is convex at its lower portion F, where it comes 45 in contact with the portion B of the case A, and threaded over its upper cylindrical portion G. The column E is connected to the containing-case D in any suitable manner. Surrounding the column E is a ring H, having a depending portion I upon one side, which is located in the slot C of the standard A. Surrounding the column E above the ring

H is a second interiorly-threaded ring J, provided with tangential arms K.

It will be observed that by reason of the arrangement described the containing-case D may be revolved horizontally around the top of the base A and that it also may be inclined at an angle to the base A by the movement of the depending portion I of the ring H in the slot C of the standard and when in this position may be revolved around the column E. By moving the threaded ring J downward the angular position of the containing-case D relative to the standard A may be fixed.

The containing-case D consists of a globular body L and the interior concave pole-pieces M. The containing-case D is provided with a fixed bearing N and removable bearing 70 O. The bearings N and O have cavities P formed therein, which communicate through openings R with the exterior of the bearings and through openings S with the interior of the bearings. The object of making the bearings with cavities, as described, is for the purpose of introducing into them any semi-solid lubricant of the character which when the bearings are slightly heated will be melted and run through the openings S and lubricate 80 the shaft T of the armature U. The bearing N occupies a fixed position relative to the containing-case D, whereas the bearing O is mounted in a disk O', which fits into an opening provided for it in the case D. The disk 85 O' is made slightly larger than the diameter of the armature U, so that when the disk O' is removed the armature may be removed through the opening in the case. This arrangement permits the easy removal of the 90 armature for inspection and repair. The sides D' of the containing-case D are formed as convex disks, which are secured to the case by means of suitable screws. These sides are perforated at D² and carry the contact-brushes V, which respectively bear upon the opposite sides of the commutator X of the armature U. The brushes V, behind which are the springs V', are carried in rectangular tubes V², having slotted heads. These tubes 100 are situated in insulated tubes carried in the side plates D'. The insulated tubes D³ are provided with bails D⁴, which when the rectangular tubes V² are in position take into

the slots in their heads. By pushing in the tubes V^2 the bails D^4 can be turned aside and the tubes V^2 , with the inclosed spring-pressed brushes, removed for the introduction of new brushes or for repairs.

Y represents the guard for the fan Z. The guard consists of the outer ring Y' , tubular spacing-columns Y^2 , inner ring Y^3 , interlaced wires Y^4 , having the threaded ends Y^5 , and the securing-nuts Y^6 . It will be observed that the ends of the interlaced wires are carried through the spacing-columns and secured by means of the nuts. The details of the construction of the guard is shown in Fig. 5.

15 The object of this construction is that all strains to which the guard is subjected will be resisted over the whole guard in a manner similar to that in which strains are resisted in a bicycle-wheel.

20 Having thus described my invention, I claim—

1. In an electric fan, the combination of a containing-case, detachable side plates, and brush-holders mounted in said side plates.

25 2. In an electric fan, the combination of a containing-case, detachable side plates, and removable brush-holders mounted in said side plates.

30 3. In an electric fan, the combination of a containing-case, detachable side plates, and brush-holders, said brush-holders consisting of an insulated tube carrying a pivoted bail, an inner removable tube with a slotted head, and a helical spring in said inner tube.

35 4. In an electric fan, the combination of a containing-case, a standard having a tubular

vertical portion concave on its interior and slotted through one side near the top, a column provided with a convex head which conforms to the concavity of the standard and a 40 cylindrical portion secured to the containing-case.

5. In an electric fan the combination of a containing-case, a standard the inner portion of the upper end of which is concave and slotted at one side, and a column connected at one end to the containing-case and provided at the other end with a convex head seated in the concavity of the standard and means for defining the position of the containing-case and column, relative to the standard.

6. In an electric fan, the combination of a containing-case, a standard having a tubular vertical portion concave on its interior and slotted through one side near the top, a column having a convex head which conforms to the concavity of the standard and a cylindrical threaded portion secured to the containing-case, a ring with a depending portion surrounding the standard, and a second 55 threaded ring located over the first-named ring.

7. In an electric fan, the combination of the containing-case, the standard, the column E, ring H and threaded ring J.

60 In testimony whereof I affix my signature in the presence of two witnesses.

JOHN TOM BESWICK.
